LOCOMOTIVE STOKER

Frank C. Pickard, Erie, Pa., assignor to The Standard Stoker Company, Incorporated, a corporation of Delaware

Application October 2, 1928, Serial No. 309,856
Renewed January 10, 1935

19 Claims. (Cl. 110—101)

The present invention relates to stoker apparatus in general and specifically to the class of stokers that are particularly adapted for use with locomotive engines.

5 The general object of the invention is to provide a new and improved stoker of the character specified by improving the conduit or conveyor system of the stoker, its fuel feeding system and also its distributor system.

10 Specific objects of the invention are to provide a novel form of intermediate conveyor element or housing whereby the passage of the fuel therethrough under the action of the feeding means is greatly facilitated and improved 15 and to provide a new and improved form of riser or discharge box, together with certain adjuncts thereto.

To the above and other ends which will subsequently appear, the invention consists in the 20 features of construction, combinations of devices and arrangements of parts, hereinafter described as especially applicable to stokers for locomotive boilers, but it will be understood that its use is not confined to any one type of firebox or boiler; 25 and the invention is particularly pointed out in the claims.

In carrying out the invention in the present instance, there is provided a novel conduit or conveyor section or housing intermediate the 30 open trough which is supported on the locomotive tender and the riser or discharge box on the locomotive, said intermediate section or housing having a curved or arcuate bottom and vertically disposed sides, thus giving it a U-shape. Preferably, however, the top of the section is covered so that ordinarily it is referred to as a D-shaped 35 housing and forms an upturned D-shaped fuel passage throughout its length. Within this housing is a feed screw whose spiral flights or threads conform in curvature with the curved bottom of the housing, and it has been found in practice that as a result of this arrangement there is little, if any, rotation of the fuel with the screw, therefore the advance or feeding of the fuel 40 through the housing without breaking up or powdering is much improved over prior construction.

Connected with the D-shaped housing or conveyor section at its forward end is a riser or discharge box which expands or flares as it rises. The lower end of the discharge box conforms in shape with the conveyor section aforesaid and at its upper end said box terminates in a mouth which is substantially oblong in shape or like a 45 rectangle with rounded corners. This mouth does

not fill the entire fire door opening but leaves a space above which is ordinarily closed by a removable cover but which affords facilities for hand stoking and access to the fire box without displacing the discharge box.

5 The discharge box terminates outside the locomotive boiler and arranged in register with the lower side of the mouth of said discharge box and extending through the fire opening into the firebox of the boiler is a distributor plate which has one or more air passages at its under side to promote cooling of its floor. The inner end portions of the plate within the firebox are formed at the sides with depressions or guide pockets which facilitate sidewise distribution of the fuel 10 while leaving a wide space on the floor or bottom of the plate for direct action from the fluid jets of the distributor system.

15 The fuel distributing jets of this invention are emitted from a distributor head or nozzle which is in the form of a plate-like element disposed between the rear of the distributor plate and the mouth portion of the discharge box.

20 The construction of the stoker apparatus of this invention is a particularly efficient and compact one, the fuel from the tender falling into the open trough portion of the conveying system from which it is fed forwardly through a crushing member which acts upon the larger lumps 25 of fuel crushing them to smaller and more suitable sizes for delivery to the firebox. The fuel after passing through the crusher is conveyed forwardly by the intermediate portion of the conveying system, the D-shape of which allows the fuel to be advanced therethrough without further materially breaking it down or pulverizing it, and delivers the fuel to the lower portion of the riser or discharge box, which as previously stated conforms in shape with the D-shaped fuel passage 30 of the intermediate conduit, said D-shape of the discharge box preventing rotation of the fuel as it begins to rise therein. The column of fuel rising in the discharge box maintains substantially the same vertical and longitudinal cross sectional area throughout, whereas the gradual flaring 35 shape of the discharge box, increasing in area toward its oblong mouth portion permits the fuel to spread out laterally, thereby reducing the possibility of rotation of the fuel and of crushing it in its travel therethrough.

40 The rear wall of the discharge box or the cover forming the hood portion thereof extends upward above the distributor plate in a substantially continuous line with its lower portion, a distance sufficient to permit the angularly advancing 45

column of fuel to rise to a height above the distributing plate, without pulverizing pressure being exerted upon it, so that the action of gravity will break the columnar formation of the fuel and 5 place the lower and forward edge of the sloping fuel face forward of the distributor head or nozzle. The jets issuing from the head will act upon the fuel to project it over the distributing plate into the firebox, thus assisting the action of gravity in 10 breaking the fuel column and creating a more or less fixed angle of repose of the fuel dependent upon the constituency of the fuel being used. Variable amounts of fuel can be delivered to either side of the firebox or to any portion thereof by 15 means hereafter more fully described.

In consequence of the improvements above generally described, there is provided a stoker which has developed marked advantages in the feeding and distribution of the fuel; and the invention 20 will be hereinafter described more in detail in connection with the accompanying drawings, in which

Fig. 1 is a fragmentary vertical longitudinal sectional view showing portions of the locomotive with its firebox and tender with the invention applied thereto;

Fig. 2 is a vertical sectional view taken on a plane indicated by the section line 2—2 in Fig. 1 and looking in the direction of the arrows at 25 said line;

Fig. 3 is a plan view of certain of the parts shown in Fig. 1 together with the actuating means for the fuel feeding system;

Fig. 4 is an enlarged fragmentary plan view of 30 certain of the parts shown in Fig. 3;

Fig. 5 is an enlarged fragmentary plan view showing the discharge box with its cover removed so as more clearly to illustrate the underlying parts;

Fig. 6 is an enlarged fragmentary vertical sectional view of the forward portion of the conveyor system including the discharge box, together with the distributor plate and distributor head;

Fig. 7 is a transverse section taken on the line 1—1 of Fig. 6, and

Fig. 8 is a similar section taken on the line 8—8 of Fig. 6.

Referring first to Figures 1 and 3, the locomotive frame is indicated generally at 10 and the locomotive tender at 11, the tender and locomotive being coupled by a coupling 12. The locomotive supports a boiler comprising a rear water leg or back wall 13 provided with a fire door opening 14 into the firebox 15 at the lower part of which is disposed a grate 16. The floor or deck of the locomotive is indicated at 17 and the floor of the fuel-bin 18 on the tender at 19, said floor as usual being in the form of adjustable sections to afford admission of the coal or other fuel at desired points to the rear portion of the fuel conduit system.

The rear portion of said system comprises an open mouthed trough 20 supported on the tender 11 and horizontally disposed, this trough being connected by a universal joint indicated generally at 21 with the rear part 22 of an intermediate conduit section or housing. Said housing or conduit section is preferably in two parts, 20 the front part 23 being slightly smaller in cross section and fitting into the part 22 so as to provide a telescopic joint to allow for longitudinal adjustments. The front portion of the housing part 23 is connected by a universal joint 24 with 25 the lower end of a riser or discharge box 25

which extends or curves upward and inclines forward, terminating in a mouth portion 26 which is approximately horizontally disposed and opposite the lower portion of the fire opening 14, its outer face being just outside the back wall 13. Above the mouth 26 and closing the upper part of the fire opening is a conventional removable cover 27 which affords access to the interior of the firebox independently of the discharge box.

As will be seen more particularly from Figure 2, the intermediate conduit section or housing is of novel shape, this statement applying both to the inner and outer sections 22 and 23. The bottom portions of the sections as indicated at 22^a, 23^a are curved or arcuate while the sides 22^b and 23^b are substantially parallel and vertical. The tops of the sides are joined by tops or cover portions 22^c and 23^c.

As will be understood particularly by inspection of Figures 2, 4-6, the lower part of the discharge box 25 where it is connected to the forward housing part 23 conforms in shape to said housing part. The rear wall and the forward wall of said box or riser are substantially parallel but the side walls expand or spread outward laterally and the top portion or mouth 26 is substantially oblong or like a rectangle but with arcuate corners. It will be noted that while the trough 20 is horizontally disposed, the housing 22, 23 inclines somewhat upward from its rear towards its front while the discharge box rises somewhat more abruptly forming an elbow of more than 90° with the housing, said discharge box as it rises also inclining forward 35 and its top curving over so that the mouth portion 26 is substantially horizontal and in register with the fire opening 14 at its lower side. The trough and the housing are disposed below the floors of the tender and the locomotive 40 while the discharge box or riser passes upward through an opening indicated at 17^a in the locomotive deck 17.

The fuel feeding system comprises two conveyor screw sections 28 and 29 jointed at 30. The 45 section 28 is disposed within the trough 20 which at its forward end may be provided with a fuel breaker 31.

The screw section 29 is arranged within the housing 22, 23 and terminates at the lower end 60 of the discharge box 25. The screw feeding elements 28 and 29 receive rotary movements for feeding the fuel through the conduit system by any suitable means, the means shown herein comprising a spur gear 32 operatively connected to the rear end of the screw section 28 and intermeshing with a pinion 33 (Fig. 3). Said pinion is connected to a driving motor 34, preferably mounted on the tender, by connecting means comprising jointed shaft sections 35, 36 65 and 37. Under operation of the motor 34 the screw feeding elements will be rotated to feed the fuel forward through the trough 20 and the conveyor section or housing 22, 23 and thence upward through the riser 25 into the control of 65 the fuel distributing means hereinafter described.

In practice it has been found by employing my novel form of intermediate conduit that the tendency of the fuel to rotate with the screw 70 as occurs in prior construction has been substantially overcome, the fuel being advanced in the conduit readily by the fuel feeding device 29 and the D-shape of the conduit overcoming any tendency of some fuel to churn round and 75

round within the housing without being advanced or fed by the screw. Such churning would not only interfere with the feed but also would tend to break up and more or less pulverize or powder the coal and thus increase the boiler stack loss.

It will be observed that there are spaces, indicated at *s* (Fig. 2), between the perimeter of the threads of the screw **29** and the side walls of the conduit section, which spaces afford room for expansion, so to speak, of the fuel as it is moved upward in the conduit by the screw action. In other words, these spaces allow the fuel to spread and prevent its packing so that it may fall or pass readily into the control of the screw threads as they turn, promoting the feeding or advance movements of the fuel and preventing it from merely churning round with the screw without advancing.

Corresponding advantages result in a more or less degree from the shaping of the riser into the form described.

The upper part of the riser in the vicinity of the mouth is of considerably greater width than the lower part, however, and this affords opportunity for control of the distribution of the fuel as it is advanced upward through the riser by the action of the feeding system.

In order to control and regulate the advance of the fuel at the opposite sides of the riser, controlling means are employed presently to be described.

In order to afford ready access to the interior of the riser or discharge box, there is provided at its upper side a movable cover plate **38** which is preferably dome-shaped or bulged as will clearly appear from Figure 6. Said plate is movable relatively to the riser and is hinged thereto as at **39**. That part of the riser carrying the hinge is made as a detachable cover **38a** and is fastened to the main body of the riser by means such as the tap bolts indicated at **38b** in Figure 4. The detachable cover **38a** is recessed as at **38c** to receive the movable cover plate **38**.

The movable cover plate **38** is interlocked with the riser by means of thumb nuts or locking devices **40** cooperating with screws **41** extending outward from the riser and passing through open mouthed slots in the cover plate. This cover plate **38** and the detachable cover **38a** form in effect the upper part or top of the riser and constitute the upper part of its mouth portion **26**.

For the purpose of controlling and regulating the rising column of fuel at the two sides of the riser **25**, a device is provided comprising a guiding device or vane **42** arranged within the riser near its upper side, said vane being mounted on a stub shaft **43** which bears in an enlargement **38a** on the movable cover **38** of the riser. The outer end of the stub shaft carries a handle **44** by which the vane may be adjusted; and disposed between the handle and the enlargement **38a** is a locking device **45** comprised in means for holding the shaft and so fixing the vane **42** in adjusted or set positions. It will be seen that by varying the position of the vane the rising column of fuel may be turned partly to one side or the other of the upper part of riser **25**. Above the guiding or directing device **42** there is provided on the cover **38** a pair of parallel transverse track-ways **46** which receive a pair of slide plates **47**, each formed with a plurality of holes or ports indicated at **48** (Figs. 4 and 6). The slide plates may be controlled by a stoking bar or other implement applied to lugs **49** extending upward

from the end portions of the plates and enabling them to be pushed in and out in their tracks so that the holes or ports **48** may be brought fully into register with, or more or less caused to cover underlying holes or ports indicated at **50** in the cover **38**.

The construction is such that adjustable air passage-ways are provided through the top portion of the mouth or the upper end of the riser, affording a draft of air passing inward towards the firebox and adapted to carry inward the top portion of the fuel in the riser with which the air current coacts. The air controlling devices comprising the ported slide plates **47** are preferably arranged in line with the angle of repose of the fuel at the top of the riser. In conjunction with the vane **42**, the independently adjustable slide plates afford means for regulating the feeding of the fuel at opposite sides of the wide or flared portion of the riser so that it may be fed as desired into the control of the distributing means.

The fuel distributing means comprises a distributor plate **51** connected at **52** at its rear side portions to the lower part of the riser **25**, the distributor plate extending horizontally inward from outside the riser to within the firebox through the firebox opening **14** and the floor of the plate being substantially in line with the lower side of the mouth of the riser. The plate **51** may be a unitary casting and is preferably formed with one or more air passages **53** extending inward just beneath the floor so as to afford more or less of a cooling effect thereon. The passages have mouths or communications indicated at **54** with the outside air; and a lip **55** prevents the air from passing between the under side of the plate and the bottom or lower side **14a** of the fire opening **14**.

An adjustable abutment in the form of a screw **56** is threaded up centrally into the under side of the distributor plate **51**, the head of said screw resting on the bottom **14a** of the fire opening, the construction being such that adjustability of the plate **51** is thereby afforded.

At its forward or inside portion within the firebox the plate **51** is provided with outwardly flaring depressions or pockets indicated at **57** assisting the sidewise distribution of the fuel as it passes inward over the plate **51**. It will be seen particularly from Figure 5 that the pockets are so spaced as to afford a wide unobstructed flat surface indicated at **51a** on the floor of the plate **51**.

The fuel distributing means further comprise a distributor head affording a particularly compact and efficient arrangement. Said head is in the form of a plate-like member **58** which is vertically disposed in an opening or space indicated at **58a** between the distributor plate **51** and the lower side of the riser **25**. The member **58** as will be seen from Figure 6 extends upward slightly above the floor of the plate **51** and is curved or rounded at its rear side so as to lessen interference with the advance of the fuel.

The member **58** is provided with a plurality of vertical passage-ways indicated at **59** and connected at their lower ends with pipes **60** leading from fluid pressure means of suitable construction and which being in common use have not been further illustrated herein. The passage-ways **59** extend upward above the floor of the plate **51**. The inner face of the member **58** is provided with a horizontal series of small holes or jet openings indicated at **61**, a plurality of said openings communicating with each of the fluid passage-ways **59** and the outer openings preferably diverging.

It will be seen that the jet openings 61 are so disposed that the fluid jets passing therethrough act directly on and in line with the fuel received on the distributing plate 51 and so as to obtain the most direct and beneficial results in sweeping and distributing it forward through the firebox opening over the fuel bed on the grate 16. The jet action is effective to blow the fuel forward and also laterally over the floor of the distributor plate 10 into the firebox, the wide space 51a facilitating even and effective distribution while the guide pockets assist in the side distribution of the fuel over the firebed.

I claim:

15. 1. In a stoker for a boiler having a firebox including an upstanding wall with a firing opening therein, a conduit extending between the source of fuel supply and the firebox of the boiler, said conduit including an intermediate section having a curved bottom, substantially vertical sides and an approximately horizontally disposed top throughout its length; and an upwardly extending discharge box connected to said section and leading therefrom to the firing opening, the lower 20 portion of said box conforming with the shape of said intermediate section, said discharge box flaring or expanding as it extends upward and its mouth portion or delivery end at the firing opening of the firebox being substantially oblong in 25 shape and a screw conveyor in the intermediate section terminating at its delivery end adjacent the lower portion of said discharge box.
30. 2. In a stoker for a boiler having a firebox including an upstanding wall with a firing opening therein, a conduit extending between the source of fuel supply and the firebox of the boiler, said conduit including an intermediate section having a curved bottom, substantially vertical sides and an approximately horizontally disposed top 35 forming an upturned D-shaped fuel passage throughout its length; and an upwardly and forwardly extending discharge box connected to said section and leading therefrom to the firing opening, the lower portion of said box conforming with the shape of said section, the rear wall and the forward wall of said discharge box being substantially parallel and the sidewalls diverging as they 40 extend upward; the mouth portion or delivery end of said discharge box at the firing opening of the firebox being substantially oblong in shape, and a screw conveyor in the intermediate section terminating at its delivery end adjacent the lower portion of said discharge box.
45. 3. In a stoker for a boiler having a firebox including an upstanding wall with a firing opening therein, the combination of a conduit system extending between the fuel supply and the firebox of the boiler, said system including a riser conduit extending upward outside the firebox and communicating with said firing opening, and a sectional cover on the riser conduit including a hinged central section provided with an adjustable air opening, said air opening being substantially in the line of the angle of discharge of the fuel from the riser.
50. 4. In a stoker for a boiler having a firebox including an upstanding wall with a firing opening therein, the combination of a conduit system extending between the fuel supply and the firebox of the boiler, said system including a riser conduit extending upward outside the firebox and communicating with said firing opening, a sectional cover on the riser conduit including a hinged central section provided with an adjustable air 55 opening,
55. 5. In a stoker, a riser conduit, a sectional cover on the riser conduit including a hinged central section provided with adjustable air openings, and air admission means including a plurality of perforated plates slidably supported at the upper portion of said central section.
60. 6. In a stoker, a riser conduit; a movable cover on the riser; air admission means including a 10 plurality of perforated plates slidably supported on the riser; and a guide vane in said riser adjustable at will to guide the rising fuel in advance of action thereon by said air admission means.
65. 7. In a stoker for a boiler having a firebox including an upstanding wall with a firing opening therein, the combination of a conduit system extending between the fuel supply and the firebox of the boiler, said system including a conduit section and an expanding riser terminating in a 15 comparatively wide mouth; means for feeding fuel through the section and upward through the riser; and means for regulating the amount of the advancing column of fuel delivered along either side of the expanded portion of the riser, said 20 means comprising a guide within the riser, and a pair of independent devices for controlling the admission of air to the upper side portions of the 25 riser.
70. 8. The combination with a firebox having an 30 upstanding wall with a firing opening therein, of a conduit system including a conveyor conduit and a riser conduit connected thereto adapted for delivery of a column of fuel to said firing opening, a screw conveyor in said conveyor conduit terminating at its delivery end adjacent the lower portion of said riser conduit, the conveyor conduit having a curved bottom, substantially vertical sides and a horizontally disposed top forming an 35 upturned D-shaped fuel passage substantially 40 throughout its length and the lower portion of said riser conduit conforming with the shape of said conveyor conduit, the rear wall and the forward wall of said riser conduit being substantially parallel and the sidewalls diverging as they 45 extend upward, and the mouth portion or delivery end of said riser conduit adjacent the firing opening of the firebox being substantially oblong in shape.
75. 9. In a conveyor system, the combination of a 50 conduit including a conveyor conduit portion and a riser conduit portion and a screw conveyor in said conveyor conduit portion, the delivery end of said screw terminating adjacent the junction of the aforesaid conduit portions and acting to force 55 material through the riser portion, the conveyor conduit portion having a curved bottom, substantially vertical sides and a horizontally disposed top forming an upturned D-shaped passage substantially throughout its length and the lower 60 part of said riser conduit portion conforming with the shape of said conveyor conduit portion, the rear wall and the forward wall of said riser conduit portion being substantially parallel and the side walls diverging as they extend upward, and the mouth or delivery end of said riser conduit portion being substantially oblong in shape.
80. 10. In a stoker, a discharge conduit, a detachable cover on the discharge conduit having a recess therein, a movable cover mounted in and closing said recess and being hinged to the first named cover, and said movable cover provided with adjustable air openings.
85. 11. In a stoker, a discharge conduit, a detachable cover on the discharge conduit having a re- 75

opening, and an adjustable guide vane disposed within the riser conduit adjacent the air opening.

5. In a stoker, a riser conduit, a sectional cover on the riser conduit including a hinged central section provided with adjustable air openings, and air admission means including a plurality of perforated plates slidably supported at the upper portion of said central section.

6. In a stoker, a riser conduit; a movable cover on the riser; air admission means including a 10 plurality of perforated plates slidably supported on the riser; and a guide vane in said riser adjustable at will to guide the rising fuel in advance of action thereon by said air admission means.

7. In a stoker for a boiler having a firebox including an upstanding wall with a firing opening therein, the combination of a conduit system extending between the fuel supply and the firebox of the boiler, said system including a conduit section and an expanding riser terminating in a 15 comparatively wide mouth; means for feeding fuel through the section and upward through the riser; and means for regulating the amount of the advancing column of fuel delivered along either side of the expanded portion of the riser, said 20 means comprising a guide within the riser, and a pair of independent devices for controlling the admission of air to the upper side portions of the 25 riser.

8. The combination with a firebox having an 30 upstanding wall with a firing opening therein, of a conduit system including a conveyor conduit and a riser conduit connected thereto adapted for delivery of a column of fuel to said firing opening, a screw conveyor in said conveyor conduit terminating at its delivery end adjacent the lower portion of said riser conduit, the conveyor conduit having a curved bottom, substantially vertical sides and a horizontally disposed top forming an 35 upturned D-shaped fuel passage substantially 40 throughout its length and the lower portion of said riser conduit conforming with the shape of said conveyor conduit, the rear wall and the forward wall of said riser conduit being substantially parallel and the sidewalls diverging as they 45 extend upward, and the mouth portion or delivery end of said riser conduit adjacent the firing opening of the firebox being substantially oblong in shape.

9. In a conveyor system, the combination of a 50 conduit including a conveyor conduit portion and a riser conduit portion and a screw conveyor in said conveyor conduit portion, the delivery end of said screw terminating adjacent the junction of the aforesaid conduit portions and acting to force 55 material through the riser portion, the conveyor conduit portion having a curved bottom, substantially vertical sides and a horizontally disposed top forming an upturned D-shaped passage substantially throughout its length and the lower 60 part of said riser conduit portion conforming with the shape of said conveyor conduit portion, the rear wall and the forward wall of said riser conduit portion being substantially parallel and the side walls diverging as they extend upward, and the mouth or delivery end of said riser conduit portion being substantially oblong in shape.

10. In a stoker, a discharge conduit, a detachable cover on the discharge conduit having a recess therein, a movable cover mounted in and closing said recess and being hinged to the first named cover, and said movable cover provided with adjustable air openings.

11. In a stoker, a discharge conduit, a detachable cover on the discharge conduit having a re-

cess therein, a movable cover mounted in and closing said recess and being hinged to the first named cover, and an adjustable guide vane disposed within the discharge conduit and supported by the movable cover.

12. In a stoker, a discharge conduit, a detachable cover on the discharge conduit having a recess therein, a movable cover mounted in and closing said recess and being hinged to the first named cover, said movable cover provided with air admission means including an adjustable air opening, and a guide vane in said conduit mounted on the movable cover and constructed to be adjustable at will to act on the fuel prior to the action thereon by said air admission means.

13. A stoker discharge conduit having its opposite ends offset with respect to each other and opening in opposed directions, said conduit changing gradually from an upturned D-shaped configuration in transverse cross section adjacent its one end to a substantially rectangular configuration in transverse cross section at its opposite end, said casing flaring or expanding from its D-shaped end to its rectangular shaped end.

14. A stoker discharge conduit having its opposite ends offset with respect to each other and opening in opposed directions, said conduit changing gradually from an upturned D-shaped configuration in transverse cross section adjacent its one end to a substantially rectangular configuration in transverse cross section at its opposite end, said conduit flaring or expanding from its D-shaped end to its rectangular shaped end and having an element of a universal joint formed therewith at its D-shaped end.

15. A stoker discharge conduit having its opposite ends offset with respect to each other and opening in opposed directions, said conduit changing gradually from an upturned D-shaped configuration in transverse cross section adjacent its one end to a substantially rectangular configuration in cross section at its opposite end, one pair of opposite walls of said conduit being substantially equidistantly spaced throughout

and the other pair of opposite walls of said conduit diverging from the D-shaped end of said conduit to its rectangular shaped end.

16. A stoker discharge conduit having its opposite ends offset with respect to each other and opening in opposed directions, said conduit changing gradually from an upturned D-shaped configuration in transverse cross section adjacent its one end to a substantially rectangular configuration in transverse cross section at its opposite end, one pair of opposite walls of said conduit being substantially equidistantly spaced throughout and the other pair of opposite walls of said conduit diverging from the D-shaped end of said conduit to its rectangular shaped end, one of said equidistantly spaced walls being recessed adjacent the rectangular shaped end of said casing.

17. In a stoker, a discharge conduit member, a detachable cover member on the discharge conduit member having a recess therein, a hinged cover mounted in and closing said recess and being hinged to one of said members, and said hinged cover being provided with adjustable air openings.

18. In a stoker, a discharge conduit member, a detachable cover member on the discharge conduit member having a recess therein, a hinged cover mounted in and closing said recess and being hinged to one of said members, and an adjustable guide vane disposed within the discharge conduit member and supported by the hinged cover.

19. In a stoker, a discharge conduit member, a detachable cover member on the discharge conduit member having a recess therein, a hinged cover mounted in and closing said recess and being hinged to one of said members, said hinged cover provided with air admission means including an adjustable air opening, and a guide vane in said conduit member mounted on the hinged cover and constructed to be adjustable at will to act on the fuel prior to the action thereon by said air admission means.

F. C. PICKARD.
